UNITED STATES PATENT OFFICE.

OSCAR BRÜNLER, OF NEW YORK, N. Y., AND EMIL CAPITAINE, OF BERLIN, GERMANY.

HYDROCARBON MOTOR.

SPECIFICATION forming part of Letters Patent No. 394,953, dated December 25, 1888.

Application filed March 23, 1888. Serial No. 268,298. (No model.) Patented in Germany January 22, 1886, No. 35,993; in England February 13, 1886, No. 2,140; in Austria-Hungary, February 16, 1886, No. 24,764 and No. 8,052; in France February 19, 1886, No. 174,261, and in Belgium February 20, 1886, No. 71,062.

To all whom it may concern:

Be it known that we, OSCAR BRÜNLER, of the city, county, and State of New York, and EMIL CAPITAINE, of Berlin, S. W. Germany, 5 have invented a new and Improved Hydrocarbon Motor, (for which I have obtained Letters Patent in the following countries: Germany, No. 35,993, January 22, 1886; Belgium, No. 71,062, February 20, 1886; France, 10 No. 174,261, February 19, 1886; Austria, No. 8,052, February 16, 1886; Hungary, No. 24,764, February 16, 1886; England, No. 2,140, February 13, 1886,) of which the following is a specification, reference being had to the annexed drawings, forming a part thereof, in which—

Figure I is a side sectional elevation. Fig. II is a plan view.

Similar letters of reference indicate corresponding parts in both the figures.

This invention has reference to motors which are worked by means of a mixture of air and finely-divided oil, or of air and finely-divided petroleum, or of air and finely-divided naphtha, and in which the air upon its admission into the cylinder operates the fine division of the oil or petroleum or naphtha. The appliance for this operation has hitherto been arranged in the cylinder or in the cylinder-cover, in which case the air entering the cylinder through the dividing or sprinkling appliance effects the fine division of the oil, petroleum, or naphtha, the cylinder at the same time being filled with a misty vapor consisting 25 of a mixture of finely-divided oil, petroleum, or naphtha. A considerable part of the fine oil, petroleum, or naphtha comes in contact with the cooled cylinder and piston surfaces in the form of small particles and adheres 30 thereto. In the case where naphtha or other readily volatile hydrocarbon is employed to drive motors the contact of the small naphtha particles with the cylinder and piston surfaces is not prejudicial, because the naphtha readily evaporates or gasifies; but when difficultly-volatilized hydrocarbons are employed for that purpose—as, for example, oil or petroleum—the contact of the oil or petroleum particles with the cooled cylinder and piston

surfaces is very prejudicial, because they do not immediately gasify.

Our invention consists in an appliance arranged within the piston for dividing or sprinkling the oil, petroleum, or naphtha, as the case may be. The air is caused to pass 55 with great velocity through the said appliance into the cylinder in the direction of the cylinder-cover.

A great advantage is obtained by the air and the finely-divided oil, petroleum, or naphtha particles it carries along with it passing from the piston in the above direction. If the cylinder-cover is not cooled, it reaches a temperature of from 300° to 400° Celsius. We do not cool the cylinder-cover. The finely- 60 divided oil, petroleum, or naphtha which comes in contact with the hot cylinder-cover is at once gasified. As the air and the finely-divided hydrocarbon passes from the piston directly toward the cylinder-cover, no wet precipitation of oil, petroleum, or naphtha takes 65 place.

A is the foundation-frame; B, the crank-shaft; B', the crank; C, the cylinder; D, the piston; D', the sprinkling or atomizing appliance for finely dividing the oil, petroleum, or naphtha. E is the exhaust-valve for the outlet of the waste gases from the cylinder; F F', toothed wheels; F², a cam for operating the exhaust-valve E, and G is a tube through 75 which the oil, petroleum, or naphtha is carried to the piston.

The piston is in connection with the crank-shaft by means of a connecting-rod in the usual way.

The sprinkling or atomizing appliance consists of the orifice d in the piston for the passage of air into the cylinder, and of the passage e for the oil, petroleum, or naphtha. The passage e being at right angles to the passage 90 d, the flap-valve k serves for closing the orifice d, and the valve m closes the passage e. The diameter of the toothed wheel F on the crank-shaft is half that of the toothed wheel F'; consequently only one revolution of the toothed wheel F' will take place for every two revolutions of the toothed wheel F. The action of the cam F², carried by the toothed wheel

F' , causes the valve E to open at every second stroke of the piston, this being effected through the rod S , one end of which is kept pressed against the periphery of the cam F^2 by the 5 spring s . The levers $S' S^2$, arranged at right angles to each other on the same shaft, are connected with the rod S and communicate motion to the exhaust-valve E .

The way in which the motor works is as follows: As in the case of "Otto's gas-motor," the combustible mixture is drawn into the cylinder during the forward stroke of the piston, compressed during the next following backward stroke, during the next forward 15 stroke the ignited gaseous mixture is expanded, and during the next following backward stroke the products of combustion ejected—that is to say, during four piston-strokes there occurs an admission of the combustible mixture, a compression of this latter, an ignition of the combustible mixture and expansion of the gases, and an ejection of the products of combustion of the gases. The air enters the cylinder through the flap-valve k 20 and orifice d , and simultaneously therewith petroleum enters from the cavity in the bottom of the piston through the valve m and passage e , and is carried along with the air in a finely-divided state, owing in a great measure 25 to the high velocity with which the air streams over the surface of the passage e . The

petroleum flows into the cavity in the lower side of the piston through the tube G . As before stated, instead of petroleum, oil, naphtha, or other hydrocarbon may be used. 35

What we claim as our invention, and desire to secure by Letters Patent, is—

1. In oil, petroleum, naphtha, and similar motors, a piston provided with an atomizer for finely dividing the oil, petroleum, naphtha, 40 or other hydrocarbon used in driving the same, substantially as described and shown.

2. In a hydrocarbon motor, the combination of the piston D , provided with the orifices d e , arranged at an angle with each other, and 45 the valves $k m$, arranged to close the orifices during the inward strokes of the piston, substantially as herein specified.

3. The combination, with the pistons D , provided with an atomizing and an oil-containing cavity, of the oil-supply tube G , substantially as specified.
